UNITED STATES PATENT OFFICE.

MCCLOUD YOUNG, OF FREDERICK, MARYLAND, ASSIGNEE TO THE
PALMETTO FIBRE COMPANY, OF ILLINOIS.

DESIGN FOR A BRUSH.

SPECIFICATION forming part of Design No. 25,895, dated August 4, 1896.

Application filed June 15, 1896. Serial No. 595,694. Term of patent 14 years.

To all whom it may concern:

Be it known that I, MCCLOUD YOUNG, a citizen of the United States, residing at Frederick, in the county of Frederick and State of Maryland, have invented and produced a new and original Design for a Brush, of which the following is a specification, reference being had to the accompanying drawings, in which—

10 Figure 1 is a side elevation of a brush embodying my improved design. Fig. 2 is a top plan view of the same. Fig. 3 is a bottom plan view of the same. Fig. 4 is a vertical transverse section on the line $x-x$ of Figs. 1 and 3.

15 The leading features of my design consist of the brush-block presenting in outline a rear flat face and a front flat face joined by outward curves at their sides and ends and bristles radiating from the opposite ends of said brush-block and terminating between the opposite ends in lines parallel to the sides of the brush-block and joining the two bodies of radiating bristles.

20 25 A represents the brush block or body, presenting in outline as viewed from the side and in section, as in Figs. 1 and 4, a flat rear face a and a flat front face b , which faces are joined at their ends by outward curves c and at their sides by similar curves d , the front face being of a width and length somewhat

less than the rear face. The bristles radiate from the opposite ends of the block, as at e , Figs. 1, 2, and 3, and as viewed from the rear, as in Fig. 2, the outline of these bristles extends around the ends of the block and joins the same by lateral lines, as at e' . The two end bodies of radiating bristles are connected by a central body of bristles f , which extend from the front face of the block, presenting, 35 as viewed from the front, as in Fig. 2, two lines g , extending inward of and parallel to the sides of the block and joining at their ends the lateral lines e' before alluded to. As viewed in cross-section, these central bristles 40 begin at the bases of the curves which join the two faces of the block, so that at the central part of the brush, between the two radiating bodies of bristles, the sides of the block 45 are exposed, presenting in outline outward 50 curves, as d , before alluded to.

Having thus described my invention, what I claim is—

The design for a brush substantially as herein shown and described.

In testimony whereof I have hereunto set my hand, this 27th day of May, 1896, in the presence of two attesting witnesses.

McCLINTOCK YOUNG.
